[57] CLAIM

The ornamental design for a shoe sole, as shown and described.

DESCRIPTION

FIG. 1 is a bottom plan view of a shoe sole showing my new design, the top plan view being substantially flat and unornamented;

FIG. 2 is a left side elevational view thereof;

FIG. 3 is a right side elevational view thereof;

FIG. 4 is a front elevational view thereof; and

FIG. 5 is a rear elevational view thereof.

The broken lines showing of a shoe upper in FIG. 2 is for illustrative purposes and forms no part of the claimed design.

FIG.1

FIG.2

FIG. 3

FIG. 4

FIG. 5
